2 SHEETS—SHEET 2.

UNITED STATES PATENT OFFICE.

AUGUSTUS D. KLAEBER, OF LONDON, ENGLAND, ASSIGNOR TO A. B. DICK COMPANY, OF CHICAGO, ILLINOIS, A CORPORATION OF ILLINOIS.

DUPLICATING-MACHINE.

1,178,161.

Specification of Letters Patent.

Patented Apr. 4, 1916.

Application filed January 23, 1915. Serial No. 3,866.

To all whom it may concern:

Be it known that I, AUGUSTUS D. KLAEBER, a subject of the King of Great Britain, residing at London, England, have invented 5 certain new and useful Improvements in Duplicating-Machines, of which the following is a specification.

My invention relates to duplicating machines and particularly to a compact portable apparatus in which the drum and coacting means for making duplicate copies, inking means, a paper supply roll mounted in position to coact with the drum and impression roller, and, if desired, a stencil 15 paper supply roll and additional paper rolls may be mounted in a compact and self-contained structure.

The principal object of my invention is to provide a device of this character which 20 may be readily transported from place to place and which will contain within itself all the necessary elements of a stencil-duplicating outfit.

Other objects of my invention reside in 25 the details of construction and combination of parts which will be more particularly described in the following specification and pointed out in the accompanying claims.

In order that my invention may be more 30 clearly understood, attention is hereby directed to the accompanying drawings forming part of this application and illustrating certain embodiments of my invention.

In the drawings, Figure 1 represents a 35 top plan view of the duplicating outfit with the cover removed, Fig. 2 represents a side elevation of the same, partly in section, the impression roller of the duplicating machine being shown in dotted lines in position 40 for feeding the paper thereto, and in full lines in inoperative position, Fig. 3 is an end elevation of the duplicating machine on an enlarged scale showing the impression roller in operative position and also 45 showing the ink-supplying brush as in operative position, and Fig. 4 is a partial end elevation of the apparatus shown partly in section.

Referring to the drawings, the base plate 50 1 carries the standards 2, 2 upon which the printing cylinder or drum 3 of usual construction is mounted upon a shaft 4. To the left of the duplicating cylinder, stand-

ards 5, 5 are mounted which are adapted to support the spindle 6 of a paper supply 55 roll 7.

The impression roller 8 is rotatably mounted on spindle 9, between a pair of arms 10, which are pivotally mounted at 11, to the standards 2 at points which are eccentric to the axis of drum 3. A coiled spring 12 is provided for each pivoted arm 10, springs 12 being secured at their lower ends to the side frames 2 at points 13, below the pivots 11 of arms 10, and at their upper 65 ends to arms 10 as shown at 14. A handle 15 may be provided for the impression roller and a transverse strengthening rod or member 16 provided between the arms 10 above the impression roller. When the 70 device is out of use and is to be transported, arms 10 may be swung to the left to an inoperative position, as shown in Fig. 2 in full lines, in which the impression roller occupies space between the paper roll 7 and 75 printing roll 3, lugs or abutments 17, 17 on frame members 2 being provided to support arms 10 in this position. Sufficient space may be provided so that when the impression roller and its handle are in this 80 position, the device may be closed by a suitable cover.

Frame members 2 are provided with lugs or abutments 18, or one such abutment 18 may be provided on one of the side frames. 85 A pawl 19 is pivoted on one of the arms 10, or, if desired, a pair of pawls 19 may be provided, one pivotally mounted upon each of the arms 10 and adapted to coact with the lugs 18. When it is desired to lead the 90 paper from roll 7 between the impression roller and the drum 3, the impression roller is moved into the position shown in dotted lines in Fig. 2, in which the impression roller is out of contact with the surface of the drum 95 and pawls 19 are in contact with lugs 18 of the frame. In this position, arms 10 are inclined somewhat to the right from the vertical and will be held in this position by the engagement of pawls 19 with their abutments until the forward edge of the paper 100 has been positioned, when pawls 19 may be raised out of engagement with lugs 18 and the impression roller dropped into its operative position as shown in Fig. 3, the springs 105 12 being so arranged as to tend to hold the

impression roller in contact with the paper on the drum in this position. A hand crank 20 on shaft 4 may be provided for rotating the drum.

5 Arms 21 are pivoted to the side frames 2 and support a brush 22 adapted to distribute ink over the surface of drum 3. A handle 23 may be provided for moving the brush. A transverse rod 24 extends between or is 10 formed integral with arms 21, and brush 22 is carried by this rod. A hook or pair of hooks 25 are pivotally mounted on rod 24 and are adapted to engage a rod or transverse member 26, which extends between 15 arms 27 of side frames 2. The brush 22 is adapted to engage the surface of drum 3 when the brush is raised to its operative position and supported by the engagement of hook or hooks 25 with bar 26. A trough 20 27 is mounted on base plate 1 in position to clean the brush 22 when the latter is in inoperative position and to collect excess ink.

The spindle 6 on paper roll 7 is removably mounted in its bearings in standards 5 as 25 shown, and the paper 28 is arranged to be led off from the top of the roll. To prevent a too rapid feed of the paper, a retarding device 29 is employed pivotally mounted at 30, 30 to the standards 5, springs 31 con- 30 nected to standards 5 and to arms on mem- 35 ber 29 serving to hold the latter pressed against the surface of the paper on roll 7.

The whole outfit is intended to be mounted within a suitable casing which may com- 35 prise a base plate 32 and a cover member 33 which may be removably secured thereto. Base plate 1 carrying the duplicating apparatus and the paper roll supports is removably mounted within this casing by suit- 40 able means such as illustrated at the right in Fig. 2. For this purpose, brackets or lugs 34 and 35 may be provided upon the casing base plate 32, the base plate 1 of the duplicating apparatus being provided with 45 suitably positioned lugs 36 and 37 to fit within brackets 34 and 35. Lugs 36 may be pro- 50 vided with fixed pins 38 which engage within slots in bracket 34 and lugs 37 are pro- vided with spring pressed pins 39 which may be engaged within corresponding holes in bracket 35 and held in such position by their springs 40.

A second casing 41 may be mounted within casing 33 as shown at the left in Fig. 2, in 55 which are carried the supplies of stencil paper and extra rolls of paper to be printed upon. A roll of stencil paper is illustrated at 42 and extra rolls of printing paper at 43 and 44. From the roll of stencil paper a 60 suitable length may be taken whenever a fresh sheet of stencil paper is desired and fitted upon drum 3. These rolls may be secured within casing 41 in any suitable manner, a convenient form of attachment being 65 illustrated as comprising the supports or

slings 45 and press fasteners 46, the slings 45 being suitably suspended from the under side of the cover of casing 41.

In the operation of the duplicating apparatus, a paper roll is fitted on the bearings 70 of standards 5, 5, and the ink distributing brush 22 is raised into engagement with the drum 3 and held therein by hooking catches 25 over bar 26. Printing ink is now poured on the brush 22 and the handle 20 turned. 75 When a sufficient quantity of ink has been supplied to the drum 3, the brush is lowered into the position shown in Fig. 2. A stencil-sheet is fitted upon drum 3 in the usual manner and impression roller 8 is raised into the 80 position shown in dotted lines in Fig. 2 with the pawl 19 in engagement with the lug 18 of the side frame. Paper is led off from roll 7 between drum 3 and impression roller 8, after which pawl 19 is lifted clear of lug 18 85 and the impression roller permitted to drop into contact with the paper on drum 3 in the position shown in Fig. 3. The operating handle 20 is now turned and the desired 90 copies produced. The paper used is prefer- 95 ably perforated in lengths approximately equal to the circumference of drum 3, the sheets being torn off at the perforations after printing. Instead of using perforated paper however, the printed copies may be separated from the web of paper in the well-known manner.

Having described my invention, what I claim as new therein and desire to secure by Letters Patent of the United States is:

1. In a duplicating machine, the combination of a frame, a rotatable drum mounted therein, an impression roller, hand-lever means carrying said roller and pivoted to said frame eccentrically to the axis of the drum and adapted to swing said roller into operative position above the drum and into inoperative position at one side of the drum, said frame having an abutment to support said means in inoperative position, and also having a second abutment; latch means carried by said means, adapted to coact with said second abutment to hold said roller in position to permit a sheet of paper to be led between the same and the top of the drum, and spring means tending to hold said roller in operative position when said latch means is released, substantially as set forth.

2. In a duplicating machine, the combination of a frame, a rotatable drum mounted 120 therein, an impression roller, hand-lever means carrying said roller and pivoted to said frame eccentrically to the axis of the drum, adapted to swing said roller into operative position above the drum and into inoperative position at one side of the drum, a pawl carried by said means, adapted to coact with the frame to hold said roller away from the drum and above the same, and a spring secured to the frame and to said means posi- 125 130

tioned to hold said roller in printing position in contact with said drum, when said pawl is released, substantially as set forth.

3. In a duplicating machine, the combination of a rotatable drum, a frame in which said drum is mounted, a support on which said frame is mounted, a paper-roll-support mounted on said support, parallel to said frame, an impression roller pivotally mounted on said frame, adapted to swing to an inoperative position between said drum and a paper roll on said paper-roll-support, to an operative position with respect to said drum, and to an intermediate inoperative position above said drum, and releasable means for holding said roller in said last-named position.

4. In a duplicating machine, the combina-

tion of a casing provided with a cover, a base plate removably secured in said casing, 20 a paper-roll-support and a duplicating machine mounted on said base plate, said duplicating machine having a drum, a pivoted impression-roller and a pivoted inking-brush, and means for positioning the said roller 25 and brush for operation adjacent the upper portion of the drum, said roller and brush occupying inoperative lowered positions when said cover is positioned on the casing.

This specification signed and witnessed 30 this 11th day of January, 1915.
